UNITED STATES PATENT OFFICE.

HERBERT E. METCALF, OF SAN LEANDRO, CALIFORNIA, ASSIGNOR TO THE MAG-
NAVOX COMPANY, OF OAKLAND, CALIFORNIA, A CORPORATION OF ARIZONA.

VACUUM TUBE.

Application filed July 23, 1924. Serial No. 727,708.

This invention relates to vacuum tubes of the three-electrode type for use as rectifiers, amplifiers, and electric wave generators. The object of the invention is to improve the construction and operation of such a device, whereby it is made more sensitive to weak oscillations, and whereby a strength and rigidity of construction may be obtained which is greatly desirable.

10 In the construction of three-electrode tubes, the practice has become quite general to employ a grid between the plate and the filament, usually in the form of a wire or plurality of wires wound in the form of a spiral, the theory being that such a grid controls the electron stream by having imposed upon it minute voltage changes. Such a grid must necessarily offer great mechanical obstruction to the electrons, and being interposed between the filament and the plate, causes the device to have a high grid plate capacity.

25 In the present invention I do not employ the usual grid form for the third electrode, but make use of a novel form and arrangement which I term a "control electrode".

30 In my invention I place the control electrode in such a position that it is not between the filament and the plate in any manner, and is therefore entirely out of the electron stream. It is so designed, however, that the effect of its minutest voltage changes are concentrated on the filament, and thus fully effect the emission of electrons from the filament, whereby extreme sensitiveness is obtained, and in the case of amplifying tubes extremely high amplification factors are obtainable.

35 Inasmuch as the control electrode in the present invention is stamped or otherwise fashioned out of a piece or pieces of metal, it is not subject to microphonic noises which are present in the type of three-electrode vacuum tube wherein the grid is composed of a plurality of wires interposed between the filament and the plate.

40 One form which my invention may assume is exemplified in the following description and illustrated in the accompanying drawings, in which

45 Fig. 1 shows a perspective view of a vacuum tube constructed in accordance with my invention, parts of the bulb being broken away for the sake of clearness;

5 Fig. 2 shows a side elevation of the same device;

6 Fig. 3 shows a sectional view in plan of the same.

7 Throughout the various figures of the drawings I show a sealed vessel or tube 10 containing plates A and A¹, a filament B, and a control electrode C. This control electrode is usually a piece of metal which has been slotted and which has had the filament inserted in the slot. The spacing between the edges of the control electrode and the filament is as close as consistent with proper commercial production, and in the case of one such tube this spacing is $\frac{1}{2}$ of an inch. I have found that with closer spacing extremely high amplification factors of the order of 15 to 30 are obtainable with closer control electrode spacing. The spacing, however, may be changed somewhat in making tubes of different characteristics, and with the proper width of the control electrode slot and the proper anode spacing, any desired characteristics for commercial use of such vacuum tubes may be obtained. The control electrode is supported on the base of the tube by means of a post 9.

8 It will be noticed that the edges of the control electrode slot do not in any way interfere with the passage of electrons to the anode from the filament or cathode, and that the entire mechanical body of the control electrode is in no way interposed between the filament and the anode, but controls the electron stream by electro-static field concentration on the filament as described in my co-pending application, Serial Number 695,681, filed February 28, 1924.

9 It has been definitely proved that superior results can be obtained by use of a control electrode as described in the present invention; higher amplification constants are available; mechanical simplicity and rugged strength have been obtained without sacrificing volume or sensitiveness; vibration which causes microphonic noises in the output circuit of such a device are practically eliminated, and the entire device is cheap to manufacture in large quantities.

10 It will be noticed that my invention employs also a double anode or plate which consists of two separate pieces of metal placed in the proper location to receive the electron stream. These anodes have a rib or depres-

sion 11 running down the entire length of the middle of the anode which receives a supporting wire 12. This rib not only serves for an attachment of the anode material to the supporting wires, but also aids greatly in stiffening such a flat surface. These supporting wires are connected together by a yoke 13, which ties the entire anode assembly together, making it extremely strong and rugged.

In the particular form illustrated, the control electrode is in the nature of a triangular-shaped metallic plate, and the filament is carried in a V-shaped slot formed in this plate, being supported at its apex by means of an arm 14 projecting out from a standard 15.

Other forms of construction than those here illustrated and described will be apparent to those skilled in the art, such as making the control electrode in the form of a bent wire or other manners, and may be

employed without departing from the spirit of my invention as disclosed in the appended claims.

What I claim and desire to secure by Letters Patent is:

1. A three-electrode vacuum tube, comprising an anode, an integral, flat, sheet-metal, control electrode of a self-supporting character, having a substantially V-shaped slot cut therein, a filament arranged in said slot, and means for supporting the filament in spaced relation to the edges of the slot.

2. A three-electrode vacuum tube comprising an anode, a control electrode stamped from a single sheet of metal and having two slots cut therein extending from the top thereof to a point near the base, means at the base of said control electrode for supporting the same, and a filament arranged in said slots.

HERBERT E. METCALF.
